UNITED STATES PATENT OFFICE.

ORANGE O. OZIAS, OF DAYTON, OHIO, ASSIGNOR TO THE COMPUTING SCALE COMPANY, OF OHIO.

DESIGN FOR A SUPPORTING MEMBER FOR SCALES.

SPECIFICATION forming part of Design No. 31,925, dated December 5, 1899.

Application filed October 30, 1899. Serial No. 735,829. Term of patent 7 years.

To all whom it may concern:

Be it known that I, ORANGE O. OZIAS, a citizen of the United States, residing in Dayton, in the county of Montgomery and State of Ohio, have produced a new and original Design for a Supporting Member for Scales, of which the following is a specification, reference being had to the accompanying drawings, forming part thereof, in which like numbers refer to like parts.

In the drawings, Figure 1 illustrates a plan view of a supporting member for a scale embodying my invention and design. Fig. 2 illustrates a front elevation view thereof. Fig. 15 3 illustrates a side elevation view thereof, and Fig. 4 illustrates a central vertical sectional view thereof in said side elevation.

My invention and design consists, essentially, of a base having a hollow projection rising from near one end thereof, two projections extending upwardly from said base and near its opposite end, and an opening in

the side of said hollow projection toward said two projections.

In said drawings, 10 represents said base, 25 and 11 the hollow projection rising from near one end of said base. 12 and 14 represent said two projections rising upwardly from near the opposite end of said base, and 15 represents said opening through the side of said 30 projection 11 toward said projections 12 and 14. Said base 10 is provided with a recess 16 in its under side and an opening 17 through its top and between said projections 12 and 14 and said opening 15. 35

What I claim is—

The design for a supporting member for a scale, substantially as shown and described.

In witness whereof I have hereunto set my hand this 10th day of October, 1899.

ORANGE O. OZIAS.
